UNITED STATES PATENT OFFICE.

RICHARD SCHMITT AND JACOB RINDLISBACHER, OF HAGEN, GERMANY.

SOUNDING-BOARD FOR PIANOS.

1,052,755.

Specification of Letters Patent. Patented Feb. 11, 1913.

Application filed May 23, 1910. Serial No. 563,033.

To all whom it may concern:

Be it known that we, RICHARD SCHMITT and JACOB RINDLISBACHER, subjects of the Emperor of Germany, and both residing at 5 Hagen, Germany, have invented a certain new and useful Improvement in Sounding-Boards for Pianos, of which the following is a specification.

This invention relates to improvements in 10 sounding boards for pianos.

A defect in pianos at present in use is the lack of stability of the usual angular sounding board. Often, even after a short time, the board yields to the stress of the strings, 15 and the full tone of the instrument is gradually lost. Many attempts have been made to impart greater stability to the sounding board. Double boards have been made, or tension devices, for example metal ties, have 20 been used for holding the board in position. These constructions, however, have not met with approval.

The present invention has for its object 25 to provide a construction of sounding board by which the above mentioned defect is completely overcome, and which at the same time allows of the bridge being carried across the center of the sounding board, whereby in the mid-portion a full tone 30 will be obtained. The mid-portion of the bridge intersects exactly the center of the board. The periphery of the board has for this purpose the form of a continuous 35 curve without corners. The uniform support of the board and absence of sharp corners render the interruption of vibration impossible.

A further great advantage of the invention 40 is the great stability obtained against the stress of the strings. This stress is distributed uniformly over the periphery from every point. In grand pianos a board of circular form may be used, but in small pianos, where there is but a limited supporting surface for the bridge in treble and 45 in bass an almost elliptic or elliptic sounding board is more suitable. In order to increase the stability of the board without diminishing the vibratory effect, the ribs are 50 preferably arranged radially, extending outwardly from a supporting ring arranged clear of the board.

In the accompanying drawings which 55 illustrate the invention, Figure 1 shows the board alone in front elevation without the

strings, and Fig. 2 is a section on the line A, B of Fig. 1 showing the board fitted in a piano. Fig. 3 is an enlarged sectional view of a portion of the sounding board showing the convexity of the ribs *f* and the 60 beveled surface of the support for the sounding board.

Referring to Figs. 1 and 2, *c* denotes the elliptical sounding board arranged in the frame *a*. By means of the ribs *f* radiating 65 from the center, which ribs are connected with a supporting ring *g* arranged clear of the board, the latter acquires a form slightly convex toward the forward side, thus offering an elastic resistance to the stress of the 70 strings, which stress owing to the elliptical form of the board is uniformly distributed in all directions. The convex shape of the sound board is obtained by reason of the edge *o* of the frame *a*, against which the 75 sound-board bears, being slightly beveled. When the sound board is fixed to such beveled support it will assume a convex shape. It will be seen that the convex front 80 faces of the ribs *f*, which are as usual glued 80 to the sounding board, together with the beveled surface *o* of the support *a*, combine to flex or convex the sounding board toward the strings. The ribs are mounted in the support *a*, as clearly shown in Fig. 3. Such 85 shaping is possible with an elliptical board and herein lies the particular advantage of the employment of such boards. An angular board for instance, although it could be bulged, could not be strained into convex 90 shape of perfectly uniform deflection which is necessary to make it too highly elastic backing for the strings. The mid-portion 95 of the bridge *e* (which is shown hollow) for the strings *s*, Fig. 2, passes through the center of the board *c*. This arrangement of the bridge *e* is rendered possible by reason of the fact that the board projects upwardly clear of and behind the tuning peg block *b*. The bass bridge *h* runs parallel with the 100 circumference of the board in the form of an arc. As is obvious, the ribs may be otherwise arranged, for instance, they may be parallel.

It will be seen by reference to Fig. 1, that 105 the sounding board has a continuously curved periphery, and that the curvature is convex throughout the periphery of the board, as regards the center of the board.

Having now described and ascertained the 110

nature of our invention what we claim and desire to secure by Letters Patent of the United States is:

1. A piano comprising in combination, an elliptical sounding board, a support therefor having beveled portions engaging opposite edges of the board and serving to convex the same toward the string side thereof, a bridge extending across the string side of the board and abreast of and across the center of the board, ribs shaped to conform to the convex deflection of and secured to and radially disposed on that side of the board opposite the string side to stiffen the board and maintain convex deflection thereof, and a frame connected with the inner ends of the ribs and disposed abreast of but out of contact with the center of the board to prevent impairment of resonance at such central portion, substantially as described.
2. A piano comprising in combination, an elliptical sounding board, supporting means for convexing the board toward the string side thereof, ribs secured to the board to stiffen the same and maintain convex deflection of the board, a bridge extending

across the center of the board on the string side thereof, and rigid means connected with the ribs and disposed abreast of but out of contact with the center of the board to prevent impairment of resonance at such central portion, substantially as described.

3. A piano comprising in combination, a sounding board having a continuously convexly curved periphery, supporting means for convexing the board toward the string side thereof, ribs secured to the board to stiffen the same and maintain convex deflection of the board, a bridge extending across the center of the board on the string side thereof, and rigid means connected with the ribs and disposed abreast of but out of contact with the center of the board to prevent impairment of resonance of such central portion, substantially as described.

In testimony whereof we affix our signatures in presence of two witnesses.
